IMPRESSION ROLLER CONTROL

Ferdinand Nigra, San Francisco, Calif., assignor
to Niagara Duplicator Co., San Francisco,
Calif.

Application May 9, 1938, Serial No. 206,768

4 Claims. (Cl. 101—118)

The invention relates to certain controls for an impression roller which is arranged to engage a sheet to be printed against a printing cylinder or drum.

5 An object of the invention is to so mount an impression roller which is freed of external bearing contact between its periods of engagement with successive sheets being printed in a continuously operating duplicator or the like as to permit 10 an axial displacement of the roller which may be urged upon it during its functioning.

Another object is to provide a means for automatically causing a working-speed rotation of the 15 impression roller while it is displaced from its operative position and so eliminate any inertia drag as the roller is first brought into engagement with a sheet to be printed on.

A further object is to provide for an automatic 20 return of the roller to its undisplaced position as it is moved between positions in which it engages a sheet and is engaged by the driving means.

The invention possesses other objects and features of advantage, some of which, with the fore- 25 going, will be set forth or be apparent, in the following description of a typical embodiment thereof, and in the accompanying drawing in which,

Figure 1 is a fragmentary side elevation of a 30 rotary duplicator mechanism having the impression roller thereof mounted and controlled in accordance with the present invention and inoperatively disposed with respect to the printing cylinder of the duplicator.

35 Figure 2 is a sectional view taken generally in a plane through the line 2—2 in Figure 1.

Figure 3 is a fragmentary sectional elevation taken in part in a transverse plane through the cylinder and in part on the line 3—3 in Figure 2.

40 The features of the present invention are incorporated in the fragmentarily shown mechanism of a duplicating machine in which a stencil 2 is carried on a rotary cylinder 3 for its printing engagement with a sheet of paper or other 45 material for receiving printing. The printing cylinder 3 is suitably supported for rotation about an horizontal axis, is restrained against axial shifting, and may be actuated by hand or by a suitable motor.

50 By reference to the drawing, it will be noted that a sheet 14 of print-receiving material which has been advanced from the top of a stack of sheet on a feed table 15 to dispose its advance end portion between pairs of upper and lower 55 feed rollers 16 and 17, is thereafter engaged by

and between said rollers and is thereby advanced further for the disposal of its front end portion between the stencil 2 on the rotary cylinder 3 and an impression roller 18, and is finally gripped between the cylinder and roller to continue the feeding movement of the sheet while the latter is being progressively printed. As shown, the impression roller 18 is supported for its free rotation on a shaft 19 which is carried by and between corresponding and rearward ends of lever-like members 20 which are intermediately pivoted on a rock-shaft 21 which is journaled in and between side frame members 5, said shaft being disposed forwardly of a vertical plane through the cylinder axis.

15 The forward ends of the lever members 20 are connected by a bar 22, and a tension spring 23 extends generally rearwardly from the bar 22 to constantly urge a resilient engagement of the impression roller 18 against the cylinder 3. The extremities of the shaft 19 and the bar 22 pivotally engage the ends of the levers 20 whereby the generally planar assembly of these members may be distorted transversely thereof if such is required to insure an even bearing of the impression roller with and along the cylinder.

20 Arms 24 extend rigidly and radially from the shaft 21 for simultaneous engagement with the bar 22 as a means to rock the levers 20 to dispose the roller 18 out of engagement with the cylinder. An arm 25 extends rigidly from the shaft 21 in angular relation to the arm 24 thereat, and a tension spring 26 is operative against the free end of the arm 24 whereby the arm 25 is resiliently urged to maintain an engagement thereof with an adjustable stop 27; it will be understood 25 that the stop 27 may determine one limit of oscillation of the shaft 21. The rocking of the shaft 21 to displace the roller 18 at the appropriate time in the feeding cycle of a sheet 14 may be effected in any suitable manner; mechanism for providing the complete cycle by and in synchronism with the rotation of the cylinder is shown and described in detail in my United States Patent No. 2,106,930 of Feb. 1, 1938.

30 The shaft 19 which carries the roller 18 is stepped adjacent its extremities to provide reduced end portions 37 and 38 terminating at annular shoulders 39 and engaged in aligned eyes provided in corresponding extremities of the arms 20 which carry the roller to and from its described operative position. An helical spring 40 encircles the shaft portion 38 and is compressed between the shaft shoulder 39 thereat and the adjacent arm 20, it being noted that the shaft portion 38 is 35

long enough to permit a longitudinal shifting of the shaft to disengage its other end from the other arm 20; in this manner, the roller 18 may be readily removed or replaced.

5 The roller 18 comprises a core tube 41 carrying a relatively thick and resilient tread 42 for engaging beneath a sheet 14 at the stencil on the cylinder. Suitable anti-friction bearing assemblies are provided in the core tube 41 at opposite 10 ends thereof, said bearings having their outer ball races 44 slidably fitting enlarged terminal portions of the tube bore and their tubular inner ball races 45 slidably receiving the intermediate shaft portion. The present arrangement for 15 closing the bearings within the tube 41 is understood to minimize the probability of ink and/or dust getting therein.

An helical spring 47 encircles the shaft adjacent its end portion 37 and inwardly of the arm 20 thereat and is compressedly engaged between the adjacent inner race 45 and a pin or key 48 extending through the shaft. The spring 47 is constantly operative to urge the roller 18 along the shaft toward a collar or stop 49 fixed on the 25 shaft, the bearing structures being such that the races thereof are restrained against relative axial movement. The normal action of the spring 47 against one race 45 results in an engagement of the shoulders 50 at the inner ends of the counter- 30 bores which receive the races 44 with the latter races to effect the engagement of the other race 45 with the shaft collar 49. It will be obvious that the springs 40 and 47 are constantly coactive to 35 yieldingly urge a retention of the roller 18 in a longitudinally centered position with respect to the levers 20 which support the shaft 19 whereby the roller 18 may be self-centering when it is free of lateral contacts. The present self-centering mounting for the roller 18 requires a minimum 40 number of parts, and may be readily assembled or disassembled because the bearing races need not be fixed to other members.

It will now be noted that the feeding speed of a sheet 14 is preferably arranged to be the 45 same as the longitudinal speed of the stencil on the periphery of the cylinder 3 whereby the sheet and stencil may move together at the same speed when the impression roller 18 presses the sheet against the cylinder for printing. The peripheral 50 speed of the operative roller 18 is, of course, the same as that of the paper sheet and the stencil during printing, the rotation of the roller then being solely controlled by the movement of the sheet portion engaging it. When the printing 55 of each sheet is completed and the roller is moved away from the cylinder, the freed roller will tend to rotate at a decreased speed whereby its 60 rotational speed must be raised to its operative value at its subsequent application to the succeeding sheet. Since any slowing down of the rotation 65 of the roller between its operative applications produces an undesirable reactive drag upon the sheet as the roller first engages the leading sheet portion, means are provided to insure a 70 constant spinning of the impression roller when it is inoperatively disposed whereby its peripheral speed at contact may be substantially or exactly equal to the speed of the advancing sheet, said means comprising a roller spinning device which

75 is hereinafter described.

At one end thereof, the core tube 41 of the roller 18 extends somewhat beyond the tread 42 of the roller, and the exposed tube portion is fluted or otherwise roughened to provide a friction roller 53. The side frame member 5 of the

duplicator structure nearest the roller 53 rotatably mounts a pair of mutually engaged friction rollers 54 and 55, the roller 54 having a resilient tread 56 and being so positioned that the friction roller 53 on the impression roller 18 is arranged to engage it only when the impression roller is disposed in its limiting position away from the cylinder 3, at which time the rollers 53 and 54 and 55 respectively comprise driven and idler and drive rollers for the impression 10 roller.

Means are provided for operating the roller 55 at such a rotative speed that the rotative speed of the impression roller 18 may, through the coaction of the idler roller 54 with the friction roller 53, be maintained at its operative value 15 at all times. As particularly shown, the drive roller 55 is provided as part of a rotary member 56 which also provides a belt pulley 57 with which a drive belt 30 is constantly engaged, said belt 20 also driving the cylinder 3 in the present instance whereby the impression roller and the cylinder may be driven synchronously from the belt 30 at any operative speed for the cylinder. The 25 present device of maintaining the operative speed of the impression roller constant permits a much faster printing rate with the duplicator than when the device is not provided, thus eliminating an unfavorable factor which has heretofore limited the operative rate of duplicators generally. 30 The movement of the impression roller between its limiting positions where it is driven by the sheet on the cylinder and by the belt 30 is relatively rapid and more or less a snap action, 35 whereby little speed is lost as the roller moves from one position to the other.

Recalling that in sheet-handling devices wherein a sheet of material is gripped and advanced between coating rollers, a very slight variation from a true cylinder of uniform cross-section of one or both rollers, or a lack of true 40 parallelism of the roller axes, or a variation in sheet thickness, and other factors, may operate to urge a lateral motion of a sheet gripped thereat whereby the sheet may be wrinkled or even torn, it will be understood that the self-centering 45 mounting of the roller 18 on and between the levers 20 permits any required shift of the roller to avoid unfavorable effects on the sheet, and that the roller is automatically recentered while 50 it is free of the cylinder and the idler roller 54. It will also be understood that the engagement 55 of the rollers 53 and 54 might also tend to effect a relative axial shifting of these rollers, this resulting in a frictional drag if the self-centering device were lacking. It will thus be understood that the permitted axial shift of the impression roller while it is engaged by the cylinder or the roller 54, and the self-centering 60 of the roller while it is free is of marked value in connection with impression rollers which operate intermittently.

From the foregoing description taken in connection with the accompanying drawing, the advantages of the construction and use of the device will be readily understood by those skilled in the art to which the invention appertains. While I have described the features and the principle of operation of a structure which I 70 now consider to be a preferred embodiment of my invention, I desire to have it understood that the disclosure is primarily illustrative, and that such changes may be made, when desired, as fall within the scope of the following claims. 75

I claim:

1. In a rotary duplicator or the like, a driven printing cylinder, an impression roller for coaction with said cylinder to press a sheet of print-receiving material against the cylinder and to be rotated solely by reason of its contact with the sheet, a frame carrying said roller for its lateral movement to and from an operative relation thereof to the cylinder, means for automatically effecting both said movements of the roller once during each operative cycle of the cylinder, and means automatically operative to maintain the rotary speed of the roller at its operative value while the roller is inoperatively disposed with respect to the cylinder.
2. In a rotary duplicator or the like, a driven printing cylinder, an impression roller for coaction with said cylinder to press a sheet of print-receiving material against the cylinder and to be rotated solely by reason of its contact with the sheet, means mounting said roller for lateral movements thereof to and from an operative relation of the roller to the cylinder, means for automatically effecting both said movements of the roller during each operative cycle of the cylinder, means actuatable to rotate the roller at a fixed speed while it is inoperatively disposed with respect to the sheet, and a common drive means for the cylinder and roller rotating means such that the rotative speed ration of the cylinder and roller may be maintained at a constant value while the roller is inoperatively disposed with respect to the cylinder.

3. In a rotary duplicator or the like, a driven printing cylinder, an impression roller arranged for its operative coaction with said cylinder to press a sheet of print-receiving paper or the like against the cylinder and to be rotated solely by reason of its contact with the sheet, means supporting said roller for lateral movements thereof between limiting positions in which it is respectively operative and inoperative with respect to the cylinder, and means coactive with the roller solely while it is disposed in its inoperative position for maintaining its operative rotary speed.

4. In a printing apparatus, a driven printing cylinder mounted against an axial shifting thereof, an impression roller disposable for its operative coaction with said cylinder to press a sheet of print-receiving material against the cylinder for printing thereon and to be rotated solely by reason of its contact with the sheet, means supporting said roller for lateral movements thereof to and from its operative position and for its independent longitudinal shifting from a normal intermediate position thereof, means coactive with the roller to maintain its operative rotary speed solely while it is disposed in a limiting inoperative position, and means constantly operative for yieldingly urging a retention of the roller in its said normal intermediate position thereof.

FERDINAND NIGRA.
